BALANCE INDICATOR FOR A WEIGHING MACHINE OR THE LIKE

Jean P. Marzendorfer, Rutland, Vt., assignor to Howe
Richardson Scale Company, a corporation of Delaware

Filed May 16, 1960, Ser. No. 60,608

Term of patent 14 years

(Cl. D52—10)

FIG. 1.

FIG. 2.

FIG. 1 is a front perspective view of a balance indicator for a weighing machine or the like showing my new design; and

FIG. 2 is a front perspective view of another embodiment of my design.

Except for the beading the undisclosed side of FIG. 1 is substantially like the side shown in FIG. 2, and the rear is a mirror image of the front. Similarly, the side not shown in FIG. 2 is substantially like the side shown in FIG. 1 (except for the absence of beading) and the rear is a mirror image of the front.

I claim:

The ornamental design for a balance indicator for a

weighing machine or the like, substantially as shown and described.
